UNITED STATES PATENT OFFICE.

EDMUND T. SOMMER, OF NORTH ATTLEBORO, MASSACHUSETTS.

DESIGN FOR A COMBINATION GEM CLUSTER AND SETTING.

Application filed June 1, 1926. Serial No. 17,896. Term of patent 3½ years.

To all whom it may concern:

Be it known that I, EDMUND T. SOMMER, a citizen of the United States, residing in North Attleboro, county of Bristol, and State of Massachusetts, have invented a new, original and ornamental Design for a Combination Gem Cluster and Setting, of which the following is a specification, reference being had to the accompanying drawing, forming a part thereof.

Figure 1 is a plan view and Figure 2 is a side elevation of a combination gem cluster and setting, showing my new design.

I claim:

The ornamental design for a combination gem cluster and setting, substantially as shown.

EDMUND T. SOMMER.
